[57] CLAIM

The ornamental design for an automatic apparatus for measuring of arterial blood pressure, as shown and described.

DESCRIPTION

FIG. 1 is a back perspective view of an automatic apparatus for measuring of arterial blood pressure showing our new design;

FIG. 2 is a front perspective view of FIG. 1;

FIG. 3 is a left side perspective view of FIG. 2;

FIG. 4 is a right side perspective view of FIG. 2;

FIG. 5 is a top plan view of FIG. 2 rotated 90°;

FIG. 6 is a bottom plan view of FIG. 1 rotated 90°.
